US0D1109323S

(12) **United States Design Patent** (10) **Patent No.:** **US D1,109,323 S**
(45) **Date of Patent:** **** Jan. 13, 2026**

(54) **DIAPER**

(71) Applicant: **St Future International Ltd (Hong Kong), Hong Kong (CN)**

(72) Inventor: **Yuming Liang, Hong Kong (CN)**

(**) Term: **15 Years**

(21) Appl. No.: **35/521,989**

(22) Filed: **Jul. 15, 2024**

(80) **Hague Agreement Data**

Int. Filing Date: **Jul. 15, 2024**

Int. Reg. No.: **DM/239107**

Int. Reg. Date: **Jul. 15, 2024**

Int. Reg. Pub. Date: **Aug. 16, 2024**

(51) **LOC (15) Cl.** **02-01**

(52) **U.S. Cl.**

USPC **D24/126**

(58) **Field of Classification Search**

USPC D24/124, 125, 126, 189; D2/701, 712, D2/733, 745, 746, 856; D5/25, 47, 53; D30/145

Primary Examiner — George J Ulsh

Assistant Examiner — Thanh Luu Wong

(57) **CLAIM**

The ornamental design for a diaper as shown and described.

DESCRIPTION

- 1.1: Front view;
- 1.2: Back view;
- 1.3: Left view;
- 1.4: Right view;
- 1.5: Top view;
- 1.6: Bottom view;
- 1.7: Front view showing the diaper in a use state with two adhesives torn apart from the waist;
- 1.8: Perspective view showing the diaper in a use state;
- 1.9: Another perspective view showing the diaper in a use state; and
- 1.10: Front view showing the diaper in a folded state.
The broken lines surrounding the mannequin are included for the purpose of defining environmental structure that forms no part of the claimed design.

1 Claim, 10 Drawing Sheets
